UNITED STATES PATENT OFFICE.

GEORGE E. LEE, OF CLEVELAND, OHIO, ASSIGNOR TO THE GEORGE E. LEE COMPANY, OF CLEVELAND, OHIO, A CORPORATION OF OHIO.

AUXILIARY MELTING DEVICE.

Application filed June 16, 1922. Serial No. 568,695.

To all whom it may concern:

Be it known that I, GEORGE E. LEE, a citizen of the United States, residing at Cleveland, in the county of Cuyahoga and State of Ohio, have invented a certain new and useful Improvement in Auxiliary Melting Devices (Case A), of which the following is a full, clear, and exact description.

The present invention relates to what may 10 be termed an auxiliary melting device for delivering melted material to a reservoir or container.

Specifically, the invention as herein disclosed is particularly adapted for use as an 15 auxiliary molten metal feeding device for use in connection with the melting pot or crucible of such a machine as a line type casting machine or type casting machine or lead and rule casting machine or a machine 20 of similar character, but it should be understood that the particular construction herein disclosed is primarily for purposes of disclosure and is not a limitation on the invention.

Reference should be had to the accompanying drawings forming a part of this 25 specification in which Fig. 1 is an elevation with portions in section showing the device of the present invention, as applied to a 30 reservoir or pot for use in connection with a line type casting machine or an analogous machine; Fig. 2 is an elevation of a switching device showing its connection with a float controlled operating arm; Fig. 3 is a 35 plan view showing the switching member, a heating coil and the connections therebetween; and Fig. 4 is a side elevation of the switching device.

Referring to the drawings, 1 indicates a 40 fixed member such as the side rail or frame of a type line casting machine or a similar machine, and at 2 the reservoir or melting pot of such a machine is shown. No other parts of the machine are herein shown, be- 45 cause they are not essential or necessary.

It will be understood that the reservoir 50 or melting pot 2 contains molten metal, and from this pot the molten metal is delivered to the type line casting machine or similar machine.

Mounted on the fixed member 1 is a bracket 3 which is provided with a hooked end portion 4 that engages over the member 1 and at another part is provided with a set 55 screw 5 by which it may bear upon the under-

side of the fixed member 1 so that it is positioned and held upon the member 1. This bracket has a hollow hub like projection 6 which is integral or forms a part of or is attached to the bracket 3, and the interior 60 of this part 6 is threaded to receive the lower end of a post 7. The upper part of the member 6 is slotted as indicated at 6^a, and there are ears 6^b made integral with the member 6 on opposite sides of the slot, 65 and these ear members may be drawn together by means of a threaded member 6^c. This exerts a pinching and holding action upon the post 7 thereby to hold it in adjusted position. At the upper end of the 70 post 6 there is a head 8 mounted upon the rod which is positioned and held upon the rod by means of a set screw 9. This head has upwardly extending ears one of which is shown at 10, and pivotally mounted upon the ears is an arm 11 which may be raised into the upper position shown in dotted lines, and when so raised, if it be desired to hold it in this position, a pin 12 may be placed beneath the arm 11, as indicated in 80 Fig. 1. The lower position of the arm 11 is regulated by means of a set screw 13 which is carried by a lip 8^a extending from the head 8.

The outer end of the arm receives an ex- 85 tension 14 from a melting cup 15, which cup at its upper end is provided with a flange 16 and upon this flange there may be mounted a barrel-like member 17, the same being held upon the flange by means 90 of studs or screws or similar devices such as indicated at 18. The member 17 is adapted to receive ingots 19 of solid material, which are fed into the crucible or melting cup 15. The melting cup 15 is provided 95 with a cylindrical portion 15^a at the upper part thereof, and a conical portion 15^b at the lower part thereof, and the end of the ingot extends within the cup 15 and as it melts 100 conforms to the inner surface of the conical portion of the cup. The internal diameter of the cylindrical portion of the cup is slightly greater than that of the ingot and hence the ingot when properly guided by the member 17 does not touch the cylindrical 105 portion of the cup but is guided directly into engagement with the conical portion of the cup.

Heat is supplied to the melting cup by an 110 electric resistance coil, which is indicated

at 20, and for this purpose the cup is preferably provided with spiral grooves upon the conical portion thereof which terminate in circumferential grooves upon the cylindrical portion thereof, and the two terminals of the heating coil are indicated at 20^a.

The melting cup or crucible is more fully described in my co-pending application Serial No. 568696 filed of even date herewith.

- 10 The crucible and heating coil is packed with heat resisting material, such as indicated at 21, and this is encased in a casing or sheath 22. The crucible is so mounted with respect to the reservoir or metal pot 2
 15 that it is directly above the same, and near the surface of the molten metal so that the molten metal which may be delivered from the crucible as the resistance heating element functions will be delivered directly
 20 to the molten metal within the reservoir 2, and protected from the air as much as possible so as to eliminate the formation of dross or other oxidation products.

Mounted adjacent to or upon the reservoir 2 is a supporting member 23. This supporting member 23 is preferably detachably carried by the reservoir. The support 23 has an upstanding part 23^a upon which is pivoted an arm 24. This arm is provided with a plurality of openings such as indicated at 24^a, and in these openings there is received a pin 25 carried by the support 23 which forms a pivotal mounting for the arm 24, and the arm is held upon the pin 25 by means of a cotter pin 26.

The arm 24 at its outer end carries a float 27 which extends within the reservoir 2, and is in position to co-operate with the molten material therein, and as the float rises and falls it moves the arm 24 about the pin 25 as a pivot. At one end of the arm 24 and beyond its pivotal point is an extending portion 28 which is pivotally mounted upon the arm 24, as indicated at 29. The portion 28 is adjustable with respect to the arm 24, and this adjustment is secured by means of two set screws such as indicated at 30, which are carried by the extension 28, and bear upon the arm 24. Adjustment of these set screws will regulate the angular position of the part 28 with respect to the arm 24. The portion 28 is formed with a reentrant slot 31.

Mounted upon the bracket 3 or in any similar convenient position is a switch member which in the present instance is a mercury switch member. This switch as shown comprises a base portion 33 and end members 34 and 35. Extending into and between the end members 34 and 35 is an outer cylindrical member 36, which is of glass, and associated with the member 36 are the end members 36^a which are preferably of metal. Inside of the member 36 is another cylindrical member 36^c which also extends

between the end members 34 and 35. In this member 36 is a small hole 36^b and except for this hole there is no communication between members 36 and 36^a. These end members 36^a have pin extensions such as indicated at 36^d by which the member 36 is mounted in the end members 34 and 35 and will turn axially.

At one end of the member 36^a is a terminal member 37 which co-operates with a conductor 38 inside of the cylindrical member 36^c. Upon the other member 36^b there is also a terminal member as indicated at 39, and it communicates with a conductor 40 which is within the cylindrical member 36^c. This cylindrical member 36 and cylindrical member 36^c are partially filled with mercury so that when the cylindrical members are turned in one position, that is with the hole 36^b downwardly, electrical communication between the electrodes 38 and 40 is established through the mercury; but when the members are moved so that the hole 36^b is up and above the level of the mercury in the tube 36, then contact is broken.

One of the members 36^b is provided with an upstanding portion 41, and the end member 35 is provided with oppositely disposed pins one of which is indicated at 42, which pins stand in the path of movement of the member 41 so as to limit the rotation of the cylindrical member 36. The member 41 has a pin 43 secured thereto, which at its outer end engages one end of a spring 44. The opposite end of the spring is attached to an extension 45^a which is carried by one arm 45 of a bell crank lever, the other arm of which is indicated at 46 in Fig. 1.

This bell crank lever is mounted upon an upright 47 which may be supported upon the bracket 3 or may be secured in any desired manner. The bell crank lever is pivoted by means of a pivot screw, such as indicated at 48. The portion 46 of the bell crank lever which has just been described has extending therefrom at substantially right angles a pin 49, and this pin is adapted to extend into the slot 31 of the adjustable arm 28 which has been previously described.

It will be seen that as the float moves in accordance with the rise and fall of the material within the reservoir 2, the arm 24 will move about its pivot and the extension 28 of the arm 24 will move the arms 46 and 45 of the bell crank lever. The float may have a considerable range of movement as may also the bell crank levers 45, 43, without causing rotation of the switch member 36, because the bell crank lever will move until the end of the spring which is attached to the lower end of the arm 45 of the bell crank lever and to the pin 43 moves beyond the center upon which the cylindrical

switch member 36 is mounted, but as soon as this takes place the spring positively and quickly rotates the cylindrical member 36, until the member 41 engages with one of the 5 stop pins 42.

It will be obvious that the arrangement is such that when the float is up, that is to say, when the level of the material in the reservoir is at the highest desired point, it 10 will operate to turn the cylindrical switch member 36 in the direction which will break the circuit between the conductors 38 and 40, and, conversely, when the float member is at a lower point within the reservoir 2 the 15 cylindrical member 36 will be so turned as to establish the connection between the conductors 38 and 40.

The relation between the parts for operating the cylindrical member 36 is such that 20 the actual application of rotary movement to the cylindrical member 36 is accomplished at substantially the extreme points of movement of the float 27.

The heating element or coil 20 has one 25 of its terminals connected with the electrode terminal 37, while the other end of the resistance coil is connected with one side of the energizing circuit. The other side of the energizing circuit may be connected with 30 the terminal electrodes 39. Therefore, the operation of the switch will serve to make or break the connection between the outside energizing circuit and the heating coil, and the float therefore directly operates the 35 switch which functions in the manner that has just been described.

Having described my invention, I claim:

1. The combination with a reservoir adapted to contain material in molten form, of 40 a melting cup mounted above the reservoir and adapted to contain material in solid form, an electric resistance element associated with said cup, an oscillating switch controlling the functioning of the resistance element, a pivoted arm, a resilient member connecting the arm with the switch, a pivoted member having operative connection with said arm, and means responsive to the level of the material in the reservoir and having 45 operative connection with the pivoted member.

2. The combination with a reservoir adapted to contain material in molten form, of 55 a melting cup mounted above the reservoir and adapted to contain material in solid form, an electric resistance element associated with said cup, an oscillating switch controlling the functioning of the resistance element, a pivoted arm, a resilient member connecting the arm with the switch, an extension carried by said arm, a pivoted member mounted adjacent the reservoir and having 60 a loose connection with the extension carried by said arm, and means responsive to the level of the material in the reservoir 65

and having operative connection with the pivoted member.

3. The combination with a reservoir adapted to contain material in molten form, of a melting cup mounted above the reservoir 70 and adapted to contain material in solid form, an electric resistance element associated with said cup, an oscillating switch controlling the functioning of the resistance element, a pivoted arm, a resilient member connecting the arm with the switch, a pivoted member mounted upon the reservoir and movable therewith said pivoted member having a loose but operative connection with the 75 said arm, and means responsive to the level of the material in the reservoir and having pivotal connection with the pivoted member.

4. The combination with a reservoir adapted to contain material in molten form, of 80 a melting cup mounted above the reservoir and adapted to contain material in solid form, an electric resistance element associated with said cup, an oscillating switch controlling the functioning of the resistance element, said switch being mounted adjacent the reservoir, an arm pivoted adjacent said switch, a resilient member connecting the arm with the switch, said arm having an extension having a pin thereon, a pivoted member mounted upon one side of the reservoir and movable therewith, said arm having a slotted portion which engages with the 85 said pin, and means responsive to the level of material in the reservoir and having operative connections with the pivoted member.

5. The combination with a reservoir adapted to contain material in molten form, of a melting cup mounted above the reservoir and adapted to contain material in solid form, an electric resistance element associated with said cup, an oscillating switch controlling the functioning of the resistance element, said switch being mounted adjacent the reservoir, an arm pivoted adjacent the 90 said switch, a spring member connecting the arm with the said switch whereby movement of the arm to move the switch is exerted through the said switch, said arm having an extension, a pin carried by said extension, a pivoted member mounted upon the side of the reservoir but movable therewith, said arm having a slotted portion which engages with the pin, said slotted portion being adjustable with respect to the pivoted member, and means responsive to the level of the material in the reservoir and having 95 operative connections with the pivoted member.

6. The combination with a reservoir adapted to contain material in molten form, of a melting cup mounted above the reservoir and adapted to contain material in solid 100 form, an electric resistance element associated with said cup, an oscillating switch controlling the functioning of the resistance element, a pivoted arm, a resilient member connecting the arm with the switch, an extension carried by said arm, a pivoted member mounted adjacent the reservoir and having 105 a loose connection with the extension carried by said arm, and means responsive to the level of the material in the reservoir and having 110 operative connections with the pivoted member.

ated with said cup, an oscillating switch controlling the functioning of the resistance element, a pivoted arm mounted adjacent the said switch and extending substantially parallel with a portion of the switch, a spring member secured to the arm at one end, said spring member being secured to the oscillating switch above the axis of its rotation, the movement of said arm to oscillate the switch being exerted through said

spring, said arm having an extension, a pin carried by the extension, a pivoted member mounted upon the side of said reservoir and having a slotted portion which engages with the said pin, and a float member within the reservoir and connected with the said arm.

In testimony whereof, I hereunto affix my signature.

GEORGE E. LEE.
